(57) **CLAIM**

The ornamental design for a rotating headlamp flashlight, as shown and described.

DESCRIPTION

FIG. 1 is a top perspective view of the rotating headlamp flashlight showing my new design.

FIG. 2 is a bottom perspective view thereof.

FIG. 3 is a front view thereof.

FIG. 4 is a back view thereof.

FIG. 5 is left side view thereof.

FIG. 6 is a right side view thereof.

FIG. 7 is a back view thereof.

FIG. 8 is a top view thereof.

FIG. 9 is perspective view of the rotating headlamp flashlight with the end rotated.

FIG. 10 is a side view of the rotating headlamp flashlight with the end rotated.

FIG. 11 is a perspective view of the rotating headlamp flashlight with the end rotated.

FIG. 12 is a back perspective view of the rotating headlamp flashlight with the end rotated; and,

FIG. 13 is a bottom perspective view of the rotating headlamp flashlight with the end rotated.

The broken line showing of a head mount in FIGS. 11, 12 and 13 is for environmental purposes only and forms no part of the claimed design.
